WILLIAM J. NEWTON, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

FLUSH SWITCH.

Application filed April 28, 1924. Serial No. 709,437.

This invention relates to electrical switches, and has for an object to provide a switch construction which may be employed for a one-way, two-way, three-way or four-way 5 switch.

It is also an object of the invention to provide a construction which by merely shifting contacts may be employed as any one of the above mentioned types of 10 switches.

It is a further object of the invention to provide an improved operating mechanism for the switch element.

With the foregoing and other objects in 15 view, I have devised the construction illustrated in the accompanying drawings forming a part of this specification, these drawings being illustrative of the preferred construction for carrying out the invention. In 20 these drawings,

Fig. 1 is a top plan view of my improved switch shown as a one-way switch.

Fig. 2 is a longitudinal section thereof substantially on line 2—2 of Fig. 1.

Fig. 3 is a similar section substantially 25 on line 3—3 of Fig. 1.

Fig. 4 is a transverse section substantially on line 4—4 of Fig. 1.

Fig. 5 is a top plan view of a switch 30 according to my invention showing a four-way construction.

Fig. 6 is a longitudinal section thereof substantially on line 6—6 of Fig. 5 but on an enlarged scale.

Fig. 7 is a similar section substantially 35 on line 7—7 of Fig. 5.

Fig. 8 is a transverse section substantially on line 8—8 of Fig. 5.

Fig. 9 is a transverse section similar to 40 Fig. 8 but showing the method of mounting a three-way jumper strap.

Fig. 10 is a wiring diagram showing the use of a one-way switch.

Fig. 11 is a wiring diagram showing the 45 use of a switch as a two-way switch.

Fig. 12 is a wiring diagram showing the use of two switches arranged as three-way switches, and

Fig. 13 is a wiring diagram showing the 50 use of three of these switches, two of them being arranged as three-way switches and the other as a four-way switch.

This invention provides an improved construction for counting the high and low box 55 contacts in a switch so that the same body

member and movable switch element may be employed for either a one-way switch, a two-way switch, a three-way switch or a four-way switch, and this result may be secured by a very simple construction which 60 may be manufactured and assembled at low cost. Referring to Figs. 1 to 4 I have shown my improved switch arranged as a one-way switch, and this embodiment comprises an insulating body member 15 in the present 65 case molded in one piece, with a pocket 16 in which the switch mechanism is mounted. I do not, however, wish to be limited to this specific construction of the body member as any of the usual forms may be employed, as 70 for instance, where the body is made in two sections secured together. The switch mechanism is secured to the bottom wall of the pocket by means of suitable screws 17 threaded into the base 18 of the bracket 19, this 75 bracket in the present case being substantially U-shaped with spaced upright side members 20. Mounted in these side members is a pivot pin 21 carrying a substantially U-shaped support 22 for one or more 80 switch members 23. In the present instance there is only one of these members shown. It is carried to swing with the support on the pivot pin, and is insulated from the support by suitable fibre washers 24. It will be noted from Fig. 4 that the arms 25 extend outside the bracket while the connecting portion 26 swings between the shoulders 27 on the side members 20 which form stops to limit the 85 swinging movement of the switch support. 90

Mounted between the arms 20 of the bracket and also carried by the pivot pin is a rocker 28. The lower portion 29 of this rocker extends to a point adjacent the connecting portion 26 of the switch support. 95 Carried by the pin 21, in the present instance between the arms of the rocker, is a coil spring 30 having free ends 31 engaging opposite sides of the portions 26 and 29 of the switch support and the rocker. Means is 100 provided for swinging this rocker on its pivot. In the present instance, the rocker above the pivot is provided with a member 32 having an opening 33 in which projects the central tooth 34 of an oscillating lever 105 or toggle handle 35 pivotally mounted in a casing 36 carried by the yoke 37 to which the body member 15 is secured in the usual manner, as by screws 38. The whole mechanism is mounted in an outlet or wall box 39 110

by the usual screws 40. The lever 35 is also provided with teeth 41 engaging the outer sides of the member 32, and as the lever is rocked back and forth the rocker is swung 5 on its pivot.

Means is provided for positively locking the switch support 22 against movement during the first part of the movement of the rocker to allow this movement of the rocker 10 to tension the spring 30, and then this locking means is positively operated to release the switch support and allow it to be swung under the action of the spring which has been tensioned to thus give a snap action 15 to the switch member. For this purpose one of the side members 20 of the basket is engaged on the edges thereof with guide ribs 42 carried by a catch 43 so that this catch may slide thereon. At its lower end this 20 slide has a projection 44 adapted to engage opposite sides of the connecting portion 26 of the switch support as shown in Figs. 2 and 3. The catch is also provided with a transverse slot 45 into which a pin 46 carried by 25 the rocker projects. It will be apparent that as the slot is straight and the pin 46 swings on an arc about the center of oscillation of the rocker, the catch 43 will be reciprocated up and down by the swinging movement of 30 the rocker. Thus in operation swinging of the lever 35 will swing the rocker. If the free end of the lever is swung to the right, as shown in Fig. 3, the bottom portion 29 of the rocker and also the pin 46 will be 35 swung to the right. The portion 29 of the rocker will swing the free end 31 of the spring which is on the right hand of this portion away from the portion 26 of the switch support and will thus tension the 40 spring. As portion 26 of the switch support engages the projection 44 of the catch the switch element will be held stationary until the pin 46 has moved to approximately the other end of the slot 45, as shown in dotted 45 lines Fig. 3, when the slide will be raised to move the projection 44 from engagement with the switch support, and the tensioned spring will swing this support on its pivot and move the switch element to the dotted 50 line position with a rapid snap action. The switch will be swung back again by a reverse movement of the lever, the support for the switch member being held against movement during the first part of the movement 55 of the lever by engagement of the portion 26 on the other side of the projection 44. This construction gives a positive lock for the switch to hold it stationary until the spring has been properly tensioned and 60 the operating lever has been moved to practically its extreme position, when the catch is positively released and the switch allowed to operate under the action of the tensioned spring.

65 I have also provided an improved mount-

ing for the stationary contacts which are engaged by the swinging switch member. For the purpose of carrying these contacts the body member is provided with spaced shoulders 47 and 48, these shoulders being spaced 70 from each other in the direction of movement of the free ends of the switch member, and contacts may be mounted on either one or both of these shoulders as desired. In the construction shown in Figs. 1 to 4, that is, 75 in the one-way construction, there are only two contacts one contact 49 being carried by the upper shoulder at one end of the body member while the other contact 50 is carried by the lower shoulder at the other end 80 of the body member, so that both of these contacts are engaged by the switch member when it is in closed position, as shown in Fig. 2. The contacts may be mounted on the shoulders by any suitable means but that 85 shown is a very simple one involving a single element, which not only secures the contacts in position on the shoulders but may also be employed to form an electrical connection between them. This securing element and connection comprises a screw 51 of sufficient length to pass from one shoulder to the other carrying high and low box contacts, and preferably passes through an opening in the lower contact and is threaded 90 into the upper contact, as shown in Fig. 2. The upper contact may also carry the binding post screw 52 to which the lead wires L are connected. It will be noted that in 95 this construction there may be a stationary contact on the upper shoulders or the lower shoulders or both as desired and that the securing screw 51 may provide an electrical connection between them. As the switch shown in Figs. 1 to 4 is a one-way switch 100 only two stationary contacts are shown and the other binding post screw 52' is electrically connected with the low box contact 50 by screw 51.

Referring now to Figs. 5 to 13 I have 110 shown how the same construction may be employed for either a two-way, three-way, or a four-way switch. In this construction an insulating body member 53 is substantially the same as the body member 15 except 115 that as this member may carry eight stationary contacts it is made of the same shape and arrangement on both sides while in Fig. 1, as there is only one switch element used the sides of the body are preferably inclined 120 inwardly, as shown at 54, to reduce the space required and also the amount of material, but I wish it to be distinctly understood that the construction shown in Figs. 5 to 8 is just as well adapted for a one-way switch as 125 is the first construction. In the form shown in Figs. 6 to 8 the switch operating mechanism is the same as in the first form except that instead of using a swinging lever projecting outwardly from the device, a pair 130

of push buttons 55 are provided which are pivotally connected to yokes 56 connected to the rocker 28 so that by pushing inwardly on these buttons the rocker is oscillating about its pivot to operate the switch the same as in the first form.

In order, however, to make this device adapted for use as a one-way, two-way, three-way or four-way switch, the body 53 10 is provided with four shoulders 57 adjacent the top of the pocket 58 in which the switch mechanism is mounted, and four shoulders 59 adjacent the bottom of this pocket corresponding to the upper and lower shoulders 15 47 and 48 of Figs. 1 to 4. The upper shoulders 57 are adapted to carry high box contacts 60 and the lower shoulders 59 are adapted to carry low box contacts 61. As in the first form there is a screw 51 extending 20 between the contacts carried by the corresponding upper and lower shoulders or that is, the corresponding high and low box contacts, and these screws may not only secure the contacts to the shoulders but may 25 also provide electrical connections between them as in the first form. The upper or high box contacts 60 may carry the binding screws 63 for connection of the lead wires. In the present case there are two screws 51 30 extending between each pair of high and low box contacts as this gives a more rigid mounting for the contacts.

In the showing of Figs. 5 to 8 there are 35 four high box contacts and four low box contacts with two switch elements all arranged to provide a four-way switch. In this arrangement the left hand high box contact, as shown in Figs. 5 to 7, are not electrically connected with the lower box contacts 40 through the screws 51, the lower contacts being insulated from the screws by the insulating bushing 64 and the insulating disc 65 placed under the head of the screw. These high box contacts are, however, each 45 electrically connected with the diagonally opposite low box contact by the jumper straps 66 shown more clearly in Fig. 8. These straps are secured to the contacts by the screws 51 as they have flat portions 67 at 50 their ends engaging the contacts and through which the screws extend. The jumper straps are insulated from each other by suitable fibre washers 68 at the point where they cross, and they may be connected by a 55 rivet 69 insulated from the straps by a suitable fibre bushing.

If it is desired to have a three-way switch instead of a four-way switch, a high box contact and a diagonally opposite low box contact at each end of the body are omitted as indicated in Fig. 12. The solid circles in this figure indicate low box contacts and the open circles high box contacts. In this arrangement one of the high box contacts is 60 electrically connected with the diagonally op-

posite low box contact by a single jumper strap 70, as shown in Fig. 9, this being called a three-way jumper strap.

Figs. 10, 11, 12 and 13 show the usual installations for the four different types of 70 switches, that is, one-way, two-way, three-way and four-way for which this device is adapted in the usual lightening circuits. A single lamp only is shown at 71 for illustration and as mentioned above the solid circles 75 indicate low box contacts and the open circles high box contacts. Fig. 10 indicates the ordinary one-way switch control and Fig. 11 the ordinary two-way control. In Fig. 12 there are two three-way switches so connected 80 that either one will control the lamp 71. This is the wiring ordinarily used for controlling a lamp from two different floors of a residence. Fig. 13 shows a wiring diagram using two three-way switches and one 85 four-way switch, and this shows the wiring for controlling the same lamp from three different floors. With this arrangement the lamp may be controlled from any floor regardless of the position of the switch on the 90 other floors. If there are more than three floors it is merely necessary to add an additional four-way switch for each additional floor. In Figs. 10 to 13 the two positions of the switch elements are shown by the dotted and heavy lines.

From the foregoing description it will be apparent that by the peculiar arrangement of the shoulders 47, 48, 57 and 59, the same construction of device may be employed for 100 any one of the four types of switches mentioned by merely arranging the high and low box contacts as required for each type and omitting them where they are not necessary. This greatly simplifies manufacture as separate molds are not required for each type, 105 but all the types may be assembled in a body member made from a single mold.

In Fig. 3, member 72 is a ground connection from the switch mechanism support to 110 screw 38 and thence to the wall box 39.

Having thus set forth the nature of my invention, what I claim is:

1. In a switch, an insulating body member, a pivoted switch element, said body member being provided with spaced shoulders adapted to carry contacts to be engaged by said element, and a securing element extending between said shoulders, said securing element being adapted to secure a contact on either shoulder or both and to provide an electrical connection between them.

2. In a switch, an insulating body member having a pocket, a pivoted switch element mounted to oscillate in said pocket, said body being provided with shoulders spaced from each other in the direction of movement of the free end of the switch element, said shoulders being adapted to carry contacts for engagement with the switch ele- 130

ment, and means for securing the contacts to said shoulders and forming an electrical connection between them.

3. In a switch, an insulating body member, 5 a pivoted switch element, means for operating said switch element, said body member being provided with spaced shoulders to carry high and low box contacts to coact with said element, and means extending between said shoulders to secure the contacts thereto.

4. In a switch, an insulating body member, a movable switch element, means for operating said switch element, said body member 15 being provided with spaced shoulders to carry high and low box contacts to coact with said element and means extending between said shoulders to secure the contacts thereto, said means being also adapted to 20 form an electrical connection between the contacts secured thereby.

5. In a switch, an insulating body member, an oscillating switch member, said body member being provided with spaced shoulders 25 for high and low box contacts to coact with the switch member, means extending between a shoulder for a high box contact and a shoulder for a low box contact adapted to secure the contacts to said shoulders, and one or more jumper straps connecting certain of 30 the contacts.

6. In a switch, an insulating body member having a pocket therein, a pivoted switch member mounted in said pocket, means to

operate said switch member, said body member being provided with shoulders adjacent the top and bottom of the pocket adapted to carry contacts to engage said switch member, and means extending between said shoulders to secure the contacts thereto. 35 40

7. In a switch, an insulating body member having a pocket therein, a pivoted switch member mounted in said pocket, means for operating said member, said body member being provided with a plurality of spaced shoulders adjacent the top of the pocket and a plurality of spaced shoulders adjacent the bottom of the socket, said shoulders being adapted to carry contacts to engage said switch member, and means for securing contacts on said shoulders. 45 50

8. In a switch, an insulating body member having a pocket therein, a pivoted switch member mounted in said pocket, means for operating said member, said body member being provided with a plurality of spaced shoulders adjacent the top of the pocket and a plurality of spaced shoulders adjacent the bottom of the pocket, said shoulders being adapted to carry high and low box contacts 55 60 respectively to engage said switch member in different positions thereof, and means extending between adjacent high and low contacts to secure them to their respective shoulders. 65

In testimony whereof I affix my signature.

WILLIAM J. NEWTON.
